UNITED STATES PATENT OFFICE.

FRANKLIN L. LANE, OF BELOIT, WISCONSIN, ASSIGNOR TO P. B. YATES MACHINE COMPANY, OF BELOIT, WISCONSIN, A CORPORATION OF WISCONSIN.

PROFILE CUTTER-HEAD.

1,287,053.

Specification of Letters Patent. Patented Dec. 10, 1918.

Original application filed September 20, 1915, Serial No. 51,540. Divided and this application filed March 31, 1916. Serial No. 87,907.

To all whom it may concern:

Be it known that I, FRANKLIN L. LANE, a citizen of the United States, residing at Beloit, in the county of Rock and State of Wisconsin, have invented certain new and useful Improvements in Profile Cutter-Heads, of which the following is a specification, the same being a division of my application Serial No. 51,540, filed September 20, 10 1915.

The invention has for its object the provision of improved means for securing the knives in place on the body of the head without unduly weakening the knife and in 15 such manner as to increase the extent to which the knives may be ground down thus lengthening their lives.

In order that the invention may be readily understood I have in the accompanying 20 drawings and in the following detailed description based thereon set forth a preferred embodiment of the same. As, however, the invention is susceptible of embodiment in other and varied constructional 25 forms without departure from the essence or spirit thereof, it will be understood that the drawing and description are to be taken in an illustrative and not in an unnecessarily limiting sense. In the drawings—

30 Figure 1 is a longitudinal section through a cutter head embodying the invention;

Fig. 2 is a transverse section on the line 2—2 of Fig. 1.

As herein illustrated the shaft is represented at 11 and the cutter head at 12. The constructional details of the mounting of the head upon the shaft, forming as they do subject matter set forth and claimed in the parent application above referred to, are not 40 herein specifically described, this particular form of mounting or other approved forms being alike adapted for use in connection with the present invention.

For the purpose of mounting the tools 45 upon the head the latter is provided with a plurality of radial projections 13 having their outer faces longitudinally scored for coöperative engagement with the correspondingly scored faces 14 of the tool bodies 15.

Each of the head projections 13 is provided with an undercut channel or T-slot 16 forming a throughway extending parallel to the plane of rotation of the head and to a

line tangent to the periphery thereof, these 55 slots extending entirely through the projection 13 and being open at both ends to the space between the adjacent projections. The tool or knife 15 has a bolt aperture 17 and in register therewith a surface recess 18. A 60 bolt 19 is adapted to be seated within the T-slot 16 with its head lying within the under-cut portion 16^a, the shank of the bolt extending upwardly through the aperture 17 into the recess 18 and receiving a nut 65 20 which is seated within the recess.

It will be readily understood that the provision of the undercut T-slot 16 extending parallel to the plane of rotation of the head enables the knife 15 to be adjusted forward 70 and backward in the operation of jointing the knives and to be gradually advanced to compensate for the wearing away and the grinding of the knife edge, the bolt traveling with the knife and the head of the bolt 75 sliding within the slot 16. This arrangement has manifest advantages over the old method of fixing the bolt in the cutter head and providing the knife with a slot which travels upon the bolt, the provision of an 80 aperture instead of a slot in the knife enabling the knife to be sharpened a great many more times and also weakening the knife less than if the same were provided with an extensive slot.

The knives having been adjusted upon the head and preliminarily secured in position by means of the bolt 19, they are shown as additionally and permanently secured in adjusted position in the manner following: At 90 each end of the head the projections 13 are provided with recesses 21 having the side walls beveled at 22, and clamps 23 are provided each of which has a lip 24 overlying the edge 25 of the knife 15, the clamp 23 95 having another lip 26, which enters the recess 21 and engages the beveled wall 22. The bolt 27 passes through the clamp 23 into threaded engagement with the head. It will be readily understood that when the 100 bolt 27 is tightened it will serve to draw the clamp 23 inward, and the coöperation of the lip 26 with the inclined wall 22 will draw the clamp radially inward thus clamping the knife against the cutter head.

The clamps 23 may be dispensed with entirely, the employment of one or more bolts 19 engaging a corresponding number of

parallel spaced T-slots 16, being sufficient to firmly hold each of the tools in place on the head.

I claim:

5. 1. The combination with a rotary tool head having an undercut slot extending parallel to the plane of rotation and open at the end, of a tool carried by said head and having an aperture extending radially of the head, and a bolt arranged in the aperture of the tool with its head within the undercut slot, whereby to permit adjustment of the tool in the plane of rotation of the head.
10. 2. The combination with a rotary tool head having undercut slots or channels forming throughways extending parallel to the plane of rotation, of tools carried by said head and having apertures extending radially of the head, and bolts arranged in the apertures of the tools with their heads
15. 20. within the undercut slots, whereby to permit adjustment of the tool in the plane of rotation of the head.

within the undercut slots, whereby to permit adjustment of the tool in the plane of rotation of the head.

3. The combination with a rotary tool 25 head having undercut slots extending parallel to the plane of rotation and open at the end, of tools carried by said head and having apertures extending radially of the head, and bolts arranged in the apertures of 30 the tools with their heads within the undercut slots, and supplemental clamping means overlying the tool ends and engaging the end of the head.

In testimony whereof I have hereunto 35 signed my name in the presence of two subscribing witnesses.

FRANKLIN L. LANE.
